EFFINGHAM H. N. WARNER, OF NEW YORK, N. Y.

Letters Patent No. 101,794, dated April 12, 1870.

IMPROVEMENT IN SHIRT-BOSOM AND WRISTBANDS COMBINED.

The Schedule referred to in these Letters Patent and making part of the same.

To all whom it may concern:

Be it known that I, EFFINGHAM H. N. WARNER, of the city, county, and State of New York, have invented a new and useful Improvement in Combined Bosom and Cuffs; and I do hereby declare that the following is a full, clear, and exact description thereof, which will enable others skilled in the art to make and use the same, reference being had to the accompanying drawings forming part of this specification, in which—

Figure 1 represents an under-side view of my improved bosom.

Figure 2 is a plan view of one of the halves of the bosom.

Figure 3 represents the same arranged as a cuff.

Similar letters of reference indicate corresponding parts.

My invention has for its object to furnish an improved bosom, which shall be so constructed that its detached halves may be used with equal facility as cuffs, so that it may be used as a bosom or as cuffs, as occasion may require; and

It consists in the bosom made in two parts so formed that they may be worn as cuffs, as hereinafter more fully described.

A are the halves or parts of the bosom, which are made separate, and in about the form shown in the drawings.

The upper end edges of the parts A are hollowed out or concaved, as shown, to correspond with the form of the neck of the wearer.

In the upper forward corner of each of the halves A is formed a button-hole, a^1 , to button upon the button of the neck-band of the shirt.

The upper edges of the two parts A are slotted, as shown, said slots, a^2 , being about the same distance from the button-hole a^1 as that button-hole is distant from the forward edge of said parts.

When wearing the parts A as a bosom, the forward edges of said parts are overlapped and connected to each other by buttons or studs in the same manner as the overlapped edges of an ordinary bosom.

The button-holes a^1 are buttoned upon the button of the neck-band of the shirt, upon which button the

ends of the neck-band of the collar B are also buttoned.

The neck-band of the collar is then passed into the slots a^2 of the parts A, so that the greater part of the upper edges of the said parts A may be upon the outer side of the neck-band of the collar B, being kept in place by the turn-over part of said collar or by the neck-tie.

In the middle part of the upper edge of the parts A is formed a button-hole, a^3 , which, when the parts A are used as cuffs, is buttoned upon the wristband button of the shirt.

In the outer lower corner of the parts A is formed a button-hole, a^4 , and in the outer edge of the upper part of the pieces A is formed another button-hole, a^5 .

The button-holes a^4 and a^5 are designed to receive the button or stud by which the parts, when used as cuffs, are secured around the wrists of the wearer, the position of the button-hole a^5 being regulated by the size of the wrist of the wearer.

The parts A may be made of linen, paper, or other suitable material, and may be made plain or plaited, as may be desired.

It will be observed that the parts of the pieces A exposed when worn as a bosom are the parts that are concealed or covered by the coat-sleeves when worn as cuffs, so that they may be worn first in the one capacity until their exposed parts are soiled, and then may be worn in the other capacity until the other parts are soiled.

Having thus described my invention,
I claim as new and desire to secure by Letters Patent—

A detachable divided shirt-bosom, the two parts A of which are provided with button-holes a^1 a^2 a^3 , by which they are attached to the shirt-sleeve to serve as cuffs, as herein set forth.

The above specification of my invention signed by me this 22d day of October, 1869.

EFFINGHAM H. N. WARNER.
